5 Claims. (Cl. 110—56)

The present invention relates to a fuel firing system for a vapor generator, and more particularly to a method of and apparatus for heating and controlling the temperature and the rate of flow of both primary and secondary air to a furnace.

In the suspension burning of solid fuels, for example, pulverized bituminous coal, the fuel is prepared as required in a pulverizer with the finished product transported directly to a furnace in a carrier stream of air which at the same time also provides the primary air for combustion. One of the common applications of pulverized coal combustion is to produce hot gases for use in generating, superheating and reheating vapor such as steam. In such services, the combustion efficiency of the fuel and the efficiency of heat transfer is highly important in providing for the lowest possible operating cost. In the preparation of the pulverized fuel, such as bituminous coal, the air delivered to the pulverizing zone of the pulverizers is advantageously preheated to effect moisture removal from the fuel during the pulverization process. For high efficiency, both as to combustion and as to heat transfer in the unit, it is desirable to preheat the primary combustion air, or carrier air, to a value necessary to effect the drying of the fuel with a minimum addition of tempering or atmosphere temperature air.

As part of the efficient combustion process, it is desirable to preheat the secondary combustion air so as to reclaim heat from the cooled gases leaving the heat exchange surfaces of the vapor generating unit. Frequently, the temperature and pressure requirements of the primary and secondary air are different and in effecting the optimum heat recovery from the gases of combustion it is desirable to maintain the temperature of the gases discharged to the atmosphere at a preselected value. It is, of course, desirable, and well known in the art, to avoid cooling the spent heating gases to a value below their dew point temperature so as to avoid corrosion in the metallic parts in contact with such low temperature heating gases.

In the present invention, the gases of combustion leaving a vapor generating, superheating and reheating unit are passed through a plenum chamber having multiple outlets for the movement of the cooled heating gases through selected flow paths to air heating units. The primary and secondary air heaters are entirely separate and are arranged in parallel with control means provided to properly divide the gas flow to the separate air heaters for selective heating of the primary and secondary combustion air. The control of gas flow is accomplished by a single valve means which selectively regulates the flow of the proper amount of gas over the heating surfaces of the primary air heater so as to maintain a substantially uniform gas outlet temperature from the air heater regardless of the flow of primary air through the primary air heater. The remainder of the cooled heating gases is passed through the secondary air heaters with the temperature of the gases leaving these heaters allowed to vary in accordance with the flow through the secondary air heaters. However, the variation in gas temperature leaving the secondary air heaters is relatively minor and is substantially equal to the controlled temperature of the gases leaving the primary air heater.

The various features of novelty which characterize our invention are pointed out with particularity in the claims

2

annexed to and forming a part of this specification. For a better understanding of the invention, its operating advantages and specific objects attained by its use, reference should be had to the accompanying drawings and descriptive matter in which we have illustrated and described a preferred embodiment of the invention.

Of the drawings:

FIG. 1 is an elevation, partly in section, of a pulverized fuel firing system constructed and arranged according to the present invention as applied in the generation and heating of vapor;

FIG. 2 is a plan, partly in section, of a portion of the apparatus shown in FIG. 1 and taken on the line 2—2; FIG. 3 is an elevation, partly in section, of a portion of the apparatus shown in FIG. 2 and taken on the line 3—3; and

FIG. 4 is a schematic showing of the air flow circuit of the apparatus shown in FIGS. 1 to 3, inclusive.

In the embodiment of the invention illustrated in the drawings, a high capacity vapor generating, superheating and reheating unit of known construction is supplied with pulverized coal from a plurality of direct firing pulverizers. The gases of combustion produced in burning the coal are passed upwardly through the unit giving up some portion of their heat content by radiation of the surrounding fluid cooled walls of the furnace. Thereafter, the gases of combustion are moved in a downward direction over and between convection heat exchange elements for discharge to the air heaters of the present invention.

As shown particularly in FIG. 1 an upwardly elongated furnace 10 having fluid cooled wall tubes 11 therein is supplied with pulverized coal through a plurality of burners 12 positioned in opposite walls of the furnace. The burners are supplied with air-borne pulverized coal from

a plurality of direct fired air swept pulverizers 13. Secondary combustion air is supplied to the furnace, through the burners, from a windbox 70 enclosing all of the burners. Preheated secondary air is delivered to the windbox 70 on each side of the furnace 10 by a duct 71. In the example shown in the drawings, ten pulverizers are used to provide the pulverized coal for the furnace. As hereinafter described, each of the pulverizers 13 is provided with primary air from a common duct or manifold 14 which transports high pressure, high temperature air to the pulverizers. A single primary air fan 15, with a duplicate fan for standby service, provides the air which is passed through a duct 19 to a tubular air heater 16, delivering heated air to the manifold 14 for selectively supplying each of the pulverizers 13 with hot primary air. A branch duct or manifold 17 opens to the discharge side of the fan 15 upstream of the primary air heater 16, with the relatively cold air from this source being also selectively controlled for delivery of tempering air to each of the pulverizers when desired.

As shown in FIGS. 2 and 3, the vapor generating unit is provided with a plurality of rotary regenerative air heaters 18. These air heaters 18 are positioned in groups of two on opposite sides of the centerline of the unit and the tubular recuperative primary air heater 16. As shown particularly in FIG. 3, each of the secondary air heaters is provided with an economizer tube section 20 upstream of the air heater and downstream of the plenum chamber 21 for the gases discharged from the convection bank of the vapor generating unit.

The plenum chamber 21 (see FIGS. 1 and 3) receives partially cooled gases from the convection bank of the vapor generator where the gases flow in parallel through separate heat exchange paths 22 and 23 divided by an upright tube baffle 24 and containing superheating and reheating surfaces (not shown). Each of the parallel gas passes is provided with dampers 25 and 26 respectively at the discharge end of the convection gas passes

65 partially cooled gases from the convection bank of the vapor generator where the gases flow in parallel through separate heat exchange paths 22 and 23 divided by an upright tube baffle 24 and containing superheating and reheating surfaces (not shown). Each of the parallel gas passes is provided with dampers 25 and 26 respectively at the discharge end of the convection gas passes

so that the distribution of heating gases through the convection bank may be controlled for regulation of superheat and reheat temperatures. The plenum chamber 21 is provided with a single, centrally located lower outlet 27 which leads to the tubular type of primary air heater 16. In addition, the plenum chamber is provided with gas outlets 28 on the rearward side of the unit which open into walls 30 defining gas flow passes directing the gas flow downwardly over the economizer surfaces 20 and into the secondary air heaters 18.

As shown in FIGS. 1 and 3, the hot gases leaving the plenum chamber 21 and moving downwardly over the economizer surfaces 20 enter the rotary regenerative air heaters 18 to pass therethrough and discharge through the gas outlet 39 for movement to a stack (not shown). The incoming air enters each of the secondary air heaters 18 through a duct 72 and is discharged through a duct 73 into a common collecting duct 74 for flow through duct 71 to the wind boxes 70.

As shown in FIG. 1, the primary air heater 16 is provided with rows of upright tubes 31 extending between upper and lower tube sheets 32 and 33, respectively. As shown, one half of the tubes 31 form a downflow path for the heating gases opening into a gas receiving and turning chamber 34 positioned below the lower tube sheet 33. The chamber 34 of the heater is divided by a partition 35 having damper means 36 of the louvre type positioned in an opening 35' in the partition. The combustion gases discharging from the downflow portion of the tubular air heater pass through the dampered opening 35' in the partition 35 and move upwardly through the remaining upflow portion of the tubes 31 to discharge through a gas outlet 37 at the top of the air heater to a stack (not shown).

A schematic drawing of the primary and secondary air flow system, with particular emphasis on the primary air flow path, is shown in FIG. 4. It will be noted that each of the regenerative secondary air heaters 18 is provided with an individual forced draft fan 40. It is intended that at rated capacity of the unit all four fans will be in operation discharging air into the secondary air preheaters 18 and thence through ducts 73 into a common secondary air duct 74.

Each of the fans 40 is provided with a bypass duct 42 bypassing the secondary air preheater 18. The bypass duct, as well as the secondary air duct 73 on the downstream side of each of the secondary air heaters 18 is provided with manually operated shut-off valves 44 and 45 respectively. An additional air discharge duct 46 is connected to the discharge side of each forced draft fan 40 before the secondary air preheater with the duct opening to the common cold primary air duct 41. This additional duct 46 is also provided with a manually operated shut-off damper 47. With the damper arrangement described, it is possible to discontinue operation of one or more of the force draft fans 40 and associated secondary air heater 18, utilizing the remaining forced draft fans to provide both the primary and secondary combustion air for the vapor generating unit.

The primary air duct 41 receives air from the forced draft fans at a temperature of 100 to 150° F. due to the work of compression of the air in the fans 40. The duct 41 is provided with connections 43 to the inlet side of the duplicate primary air fans 15. Either one of the primary air fans has a capacity sufficient to supply primary air to all of the ten pulverizers serving the vapor generating unit. The inlet connection 43 leading to each of the primary air fans 15 is provided with a control damper 50 while each of the outlet ducts 51 from each of the fans is provided with a manually controlled shut-off damper 52 adjacent the fan outlets and before the outlet ducts are combined for discharge into the tubular primary air heater 16.

The air passed through the primary air heater 16 is discharged into a common hot primary air manifold 14

which in turn is provided with a duct connection 53 to each of the pulverizers. The primary air system is also provided with a bypass duct 54 opening to the outlet side of the primary air fan 15 ahead of the air heater 16 and discharging tempering air to the manifold 17 which is likewise provided with individual offtake pipes or ducts 55 leading to each of the pulverizers 13.

With the arrangement described, the flow of air through the primary air fan 15, the tubular air heater 16 and the primary air manifolds 14 and 17 is regulated in accordance with the requirements of the temperature and quantity of air necessary to operate the pulverizers in use. In this connection, it will be noted in both the schematic showing of FIG. 4 and in FIG. 1 that control dampers 56 and 57 are provided in the ducts 53 and 55 leading to each pulverizer while a total primary air flow control damper 58 is located adjacent the pulverizer inlet.

In the operation of the pulverizers, the positioning of the total air flow control damper 58 is regulated in accordance with the fuel requirements from each pulverizer. The pulverizer control system used in the illustrated embodiment of the invention is similar to that disclosed in U.S. Patent 1,965,643 where the rate of coal flow to the pulverizer is regulated in predetermined ratio to the rate of primary air flow to the pulverizer.

A separate temperature control is provided for each of the pulverizers where the temperature of the coal and air mixture leaving each pulverizer is measured and recorded. This controller 60 (see FIG. 1) may be adjusted for any desired coal and air mixture temperature leaving the pulverizer as, for example, 150° F. The temperature controller 60 thus regulates the positioning of the dampers 56 and 57 in the hot air duct 53 and the tempering air duct 55 leading to each pulverizer. For example, if the temperature of the coal and air mixture leaving a pulverizer falls below the preset value of the controller 60, the control will move the damper 57 in a closing direction and move simultaneously, in an opening direction, the hot air damper 56. The end effect of this damper regulation will be to increase the temperature of the air entering the pulverizer and with stabilized conditions within the pulverizer, the temperature of the coal and air mixture leaving will also be raised to the selected preset value.

The temperature regulation, as described in the preceding paragraph is, of course, dependent upon the availability of sufficient high temperature air in the hot air manifold. Any increase in flow through the hot air manifold will tend to decrease the temperature of the heating gases leaving the outlet 37 from the tubular air heater 16. Under these conditions, it will be necessary to increase the flow of heating gases through the air heater 16 to avoid corrosion difficulties and to compensate for the need for additional high temperature air. This is accomplished by the control arrangement shown in FIG. 1. It is, of course, understood that higher air temperature can be obtained at the expense in overall unit efficiency by operating at a higher primary air heater gas outlet temperature.

As shown in FIG. 1, the temperature of the air entering the primary air heater 16 is measured by a thermostatic transmitter 61 and the impulse transmitted to an averaging relay 62 where the impulse is joined by an impulse representative of the temperature of the gases leaving the primary air heater as measured by a thermostatic transmitter 63. The averaged impulse transmitted by the averaging relay 62 is passed through a standardizing relay and a manual selector switch and is effective in actuating an air heater damper control drive 64 which in turn adjusts the position of the damper 36 shown in FIG. 1. Repositioning the damper 36 in accordance with the average of the gas outlet and air inlet temperatures will increase or decrease the flow of gases through the primary air heater 16 and thereby increase or decrease the temperature of the air delivered by the heater.

It will be recognized that under stabilized operating conditions, an increase in the gas flow through the pri-

mary air heater 16 will decrease the corresponding flow of gas through the secondary air heaters 18. However, the effect of decrease or increase in gas flow through the secondary air heaters is relatively inconsequential with respect to the temperature of the air leaving the secondary air heaters. This is due to the comparatively small percentage of the total gas which passes through the primary air heater. Ordinarily, the primary air heater 16 will receive between 15 and 20% of the total gas flow discharging from the vapor generating unit, and a slight change in the primary air heater gas flow will, from a percentage viewpoint, result in only a minor fractional change in the total gas flow through the secondary air heaters 18, with slight change in the exiting air or gas temperatures.

In the embodiment of the invention shown in the drawings, the boiler unit has a rated continuous capacity of 3,850,000 pounds of steam per hour at a superheater outlet pressure of 2450 p.s.i.a. and a temperature of 1050° F. The re heater of the unit will heat 2,750,000 pounds of steam per hour at a pressure of 485 p.s.i.a. (leaving), with the entering steam temperature at 687° F. and with a leaving temperature of 1003° F. Under these conditions, 427,000 pounds of coal per hour will be burned and the flue gas weight leaving the secondary air heaters will be 4,615,000 pounds per hour, while 3,587,000 pounds of air will be heated to a temperature of 550° F. The weight of a gas passed through the primary air heater will be 393,000 pounds per hour (for maximum air temperature of 580° F.), while the quantity of primary air will be 703,000 pounds per hour.

With a primary air temperature of 580° F., the pulverizers can successfully handle coal having a surface moisture content of as much as 12% during the pulverization process. Under usual operating conditions, the actual moisture content will be less and 580° F. air temperature will be unnecessary. Thus, the temperature of the air entering the pulverizer may be lower, with the lower temperature attained by reducing the rate of gas flow through the primary air heater, so as to obtain lower air temperatures leaving the air heater. Alternatively, the hot air entering the pulverizer may be tempered by admitting tempering air from duct 17 so that the mixture will be at a temperature corresponding to the selected coal-air mixture temperature leaving the pulverizer. With the blending of hot and cold air to attain a desired air temperature, the rate of air flow through the primary air heater will be reduced so that the control will also reduce the rate of hot gas flow therethrough to maintain the desired gas outlet temperature.

In the preferred operation of the apparatus, the temperature of the hot air to the pulverizer will closely approximate the air temperature required to process the fuel during pulverization, and a minimum amount of tempering air will be used. It will be understood that some tempering air may be required however since the moisture content of the fuel delivered to individual pulverizers may differ, thus requiring a slight difference in the air temperature delivered to individual pulverizers. Highest overall unit efficiencies will be attained when a minimum amount of tempering air is used in the primary air delivered to the pulverizers.

While it is recognized that the foregoing relates to stabilized operation of a steam generating unit, it will be observed that the control apparatus here disclosed will function in an analogous manner to provide the predetermined primary air temperature required for the usual load range of a unit and for customary variations in the characteristics of the fuel.

While in accordance with the provisions of the statutes we have illustrated and described herein the best form and mode of operation of the invention now known to us, those skilled in the art will understand that changes may be made in the form of the apparatus disclosed without departing from the spirit of the invention covered by our claims, and that certain features of our invention may

sometimes be used to advantage without a corresponding use of other features.

What is claimed is:

1. In a pulverized fuel system comprising, a furnace, a plurality of burners in said furnace, a plurality of pulverizers supplying said burners with air-borne fuel, means forming a gas passage to receive the gases produced in said furnace, a secondary air heater disposed in said passage in which secondary combustion air is heated by gases produced in said furnace, an economizer means disposed in said passage upstream of said secondary air heater, means for causing secondary air to flow through said air heater to each of the burners at a predetermined pressure, a separate air heater in which primary air is heated by indirect contact with heating gases from said furnace, said primary air heater disposed in said passage and said secondary air heater with economizer means being arranged in parallel relationship relative to heating gas flow in said passage, means including a primary air line for causing primary air to flow through said primary air heater to the pulverizers and thence to said burners, and means for regulating the rate of flow of heating gas through said primary air heater in accordance with the difference in the temperature of the gases leaving said primary air heater and the temperature of the air entering said primary air heater while the remainder of said heating gas passes through said secondary air heater.
2. In a pulverized fuel system comprising, a furnace, a plurality of burners in said furnace, a plurality of pulverizers supplying said burners with air-borne fuel, means forming a gas passage to receive the gases produced in said furnace, a secondary air heater disposed in said passage in which secondary combustion air is heated by gases produced in said furnace, means for causing secondary air to flow through said air heater to each of the burners at a predetermined pressure, a separate air heater disposed in said passage in which primary air is heated by indirect contact with heating gases from said furnace, said primary air heater and said secondary air heater being arranged in parallel relationship relative to heating gas flow in said passage, means including a primary air line for causing primary air to flow through said primary air heater to the pulverizers and thence to said burners, and means for regulating the rate of flow of heating gas through said primary air heater in accordance with the difference in the temperature of the gases leaving said primary air heater and the temperature of the air entering said primary air heater while the remainder of said heating gas passes through said secondary air heater.
3. A pulverized fuel system according to claim 2 including means for introducing cold primary air into each of said pulverizers, and means for regulating the rate of flow of hot and cold primary air to each of said pulverizers.
4. A pulverized fuel system according to claim 3 where in the rate of flow of hot and cold primary air to each of said pulverizers is regulated in response to the temperature of the fuel and air mixture leaving each of said pulverizers.
5. The method of operating a pulverized fuel fired vapor generating and heating unit having a furnace, a plurality of burners in said furnace, a plurality of pulverizers supplying said burners with air-borne fuel, a secondary air heater in which secondary combustion air is heated by gases produced in said furnace, means for causing secondary air to flow through said air heater to each of the burners at a predetermined pressure, a separate air heater in which primary air is heated by indirect contact with heating gases from said furnace which comprises burning pulverized fuel in said unit to produce high temperature heating gases, cooling said high temperature gases in the generation and heating of vapor, passing a portion of said cooled heating gases through a primary air heating zone and thence to the atmosphere, passing the heated primary air from said primary air heating zone through

a pulverizing zone in a quantity in selected ratio to the fuel being pulverized in said pulverizing zone, passing the mixture of primary air and pulverized fuel to said vapor generating and heating unit, passing the remaining portion of said cooled heating gases through a secondary air heating zone and thence to the atmosphere, passing said heated secondary air from said secondary air heating zone to said vapor generating and heating unit to combine with said pulverized fuel in producing said high temperature heating gases, and controlling the quantity of cooled heating gases passed through

said primary air heating zone in direct response to changes in the differential temperature of the air entering and the gas leaving said primary air heating zone.
